UNITED STATES PATENT OFFICE.

CONYERS BUTTON, OF PHILADELPHIA, PENNSYLVANIA.

DESIGN FOR SCARF.

Specification forming part of Design No. **6,674**, dated May 27, 1873; application filed May 13, 1873.

To all whom it may concern:

Be it known that I, CONYERS BUTTON, of Philadelphia, Pennsylvania, have invented a Design for a Scarf, of which the following is a specification:

The figure in the accompanying drawing represents a section of the full width of the scarf, of sufficient length to clearly illustrate the design, which consists of a central stripe, A, and of two side stripes, B B, the latter consisting simply of two rows of short bars, staggered, as shown.

The stripe A is composed of a broad central band ornamented at the edges, as shown, and

relieved by a stripe similar to the stripes B extending longitudinally throughout the said band.

Irrespective of the colors employed, I claim—

The design for a scarf, substantially as described, and as represented in and by the accompanying drawing.

In testimony whereof I have signed my name to this specification in the presence of two subscribing witnesses.

CONYERS BUTTON.
